Inventor

Edwin R. Hayden

By *Laasy & Laasy, Inc. Atty.*

UNITED STATES PATENT OFFICE.

EDWIN REYNOLDS HAYDEN, OF NORTH PRESTON, VICTORIA, AUSTRALIA, ASSIGNOR OF ONE-THIRD TO BENJAMIN THOMAS ROY CHADD AND ONE-THIRD TO WILLIAM HENRY JOHN BAILEY, BOTH OF IVANHOE, MELBOURNE, AUSTRALIA.

MANUFACTURE OF BOOTS AND SHOES.

Application filed October 9, 1924. Serial No. 742,689.

To all whom it may concern:

Be it known that I, EDWIN REYNOLDS HAYDEN, a subject of the King of Great Britain and Ireland, residing in the post town of North Preston, a suburb of the city of Melbourne, in the county of Bourke, State of Victoria, Commonwealth of Australia, have invented certain new and useful Improvements Relating to the Manufacture of Boots and Shoes, of which the following is a specification.

This invention relates to the manufacture of boots and shoes and more particularly to that class of footwear generally referred to as "pumps."

Pump soled shoes have the advantage of being more flexible and consequently more comfortable to wear than footwear generally known as "Blake stitched" shoes, the uppers of which are secured to an insole, after which an outer sole is stitched to the upper and insole.

According to existing methods a pump soled shoe requires especial care and high class skilled labor to produce. The upper is turned inside out in which condition the sole is applied after which it is reversed to its normal condition. This operation involves considerable time and labor. It has also been found difficult to produce pump shoes of regular shape and fit.

The present invention involves a method of manufacturing boots and shoes whereby an article having all the advantages and flexibility of pump soled shoes may be produced but without the necessity of reversing the upper to apply the sole and whereby the insole is entirely eliminated thereby saving time, labor and material and resulting in the production of a boot or shoe having all the beneficial characteristics of a pump soled shoe without its disadvantages and at a much reduced cost.

Furthermore by the method in accordance with the present invention it is possible to produce an article which will be more accurate in shape and fit and to do so with practically unskilled labor.

The invention primarily resides in the

production of a sole split at its edges to 50 thereby form a lip and recess which latter accommodates the lower edge of the upper and in securing the upper to the sole by first inserting said edge of the upper into the said recess and subsequently stitching 55 through the lower portion of the sole edge the upper and the aforesaid marginal lip, thereby forming a three ply joint which is stronger and more efficient than the ordinary pump sole joint and eliminates the disadvantages attendant on the manufacture of 60 pump shoes.

Referring to the drawings which form part of this specification:—

Figure 1 is a perspective view of a sole 65 which has been split or cut at its edge near its inner or upper surface to form a lip which is turned up for use in accordance with the present invention.

Figure 2 is a cross section of a sole, after 70 it has been cut or split as aforesaid but before the lip formed by the splitting operation has been turned up to receive the upper.

Figure 3 is a cross section of the sole, showing the marginal lip, produced by the 75 split or cut, turned up to form a V shaped recess between the lip and the body of the sole as in Figure 1.

Figure 4 illustrates a stage in the manufacture of a shoe in accordance with the 80 invention and shows the shoe upper with interior lining placed upon a last so that the edges of the upper and lining may be entered into said V shaped recess and temporarily secured between the lip and the 85 marginal portion of the sole body preparatory to the final stitching or sewing operation. Portions are broken away to show the upper and lining within the marginal recess of the sole at the forepart of the 90 shoe and a reinforcing member or shank inserted at the rear part thereof. The heel which is subsequently attached to the shoe is indicated by the broken lines.

Figure 5 is a cross section taken in line 95 A—A of Figure 4.

Figure 6 is an inverted plan of the shoe after removal from the last and shows the

2
upper and lining permanently attached by stitching to the sole at the forepart of the shoe and the upper and lining attached to the sole and the reinforcing shank at the 5 rear part of the shoe. A portion of the sole is shown in sections and portions are broken away for convenience in illustration.

Figure 7 is a cross section of the forepart of the shoe after it has been removed from 10 the last and the upper and sole permanently sewn together by stitches passing through the body portion of the sole, the upper and its lining and the marginal lip of the sole in accordance with the invention.

15 Figure 8 is a cross section of the rear part of the shoe showing the upper secured between an internal reinforcing member or shank and the sole.

In carrying the invention into effect the 20 edge of the sole 2 of the shoe is split or cut inwardly adjacent its inner or upper surface as indicated at 3 in Figure 2 so as to form a thin integral lip 4 which is turned up around the outer face of the sole as in Figures 25 1 and 3. This lip extends around the edge of the sole preferably from the waist to the toe as clearly shown in Figure 1, but may, if desired, be extended around the whole margin of sole including the heel portion 30 thereof. The splitting of the sole and upturning of the lip in the above manner creates a V-sectioned recess 6 (Figure 3) between the aforesaid lip 4 and the lower marginal portion 7 of the sole which portion 35 7 is preferably thicker than said lip 4. This recess is utilized to accommodate the lower edge of the upper as hereinafter described.

The under surface of the sole may also be 40 provided with the usual groove or channel 8 to accommodate the stitching which unites the sole to the upper.

To produce a shoe according to the present invention the sole is damped in the usual manner after which the upper 11, with a suitable interior lining 12, if required, is placed 45 upon a last 13 (Figures 4 and 5) to which the split sole 2 has been temporarily attached by tacks or the like.

The edges 14 of the upper 11 and lining 12 50 overlap or overhang the bottom of the last 13 for a sufficient distance to enable said overhanging or overlapping edges 14 to be placed within the V-shaped recess 6 between the lip 4 and the adjacent marginal portion 55 7 of the sole. The upper is then temporarily secured to the sole 2 preferably by a suitable adhesive solution or by other suitable means such as tacks or the like. The upper with the sole thus temporarily attached is now removed 60 from the last. In this condition the sole and the upper are sewn together by the usual shoe sewing machine the stitches 16 entering the sole through the stitch channel 8 on its outer or bottom surface thence passing through the upper 11 and its lining, and

the aforesaid lip 4 of the sole and back again through these superimposed members so that the upper is securely attached between the lip 4 and the lower marginal portion 7 of the sole.

If desired the waist and the heel portion of the sole may be attached to the upper 11 and lining 12 in a similar manner to that described above but preferably a reinforcing member or shank 17 as seen in Figures 4, 6 and 8 is introduced within the waist and heel portion of the shoe and may be secured in the desired position to the upper and lining at the rear part of the shoe by tacks or the like 18 as indicated in Figure 6. The rear part of the sole 2 is subsequently attached to the upper and lining and the reinforcing shank 17 by nails or like fastening devices indicated at 18 in Figures 6 and 8, the upper and its lining being thus secured between the sole and the shank at the waist and heel part of the shoe.

Having now described my invention what I claim as new and desire to secure by Letters Patent is:—

1. A boot or shoe comprising a sole split inwardly along its edge to form a thin marginal lip extending around the fore-part of the sole at its upper surface and terminating near the waist portion thereof, the waist and heel portions of the sole being left intact, and an upper having the lower edge portion of its forward portion inturned within the recess thus formed between said lip and the lower marginal portion of the sole beneath said lip, said inturned portion of the upper being secured between said lip and lower marginal portion of the sole by means of stitches passing through the three superimposed members, and a reinforcing shank disposed within the upper and extending from a point adjacent the ends of said lip to the heel of the shoe, the waist and heel portions of the upper having its lower edge portion turned beneath the shank and secured between the shank and the sole.

2. The method of manufacturing a boot or shoe which consists in slitting the fore-part of the sole inwardly along its edge adjacent its upper surface to produce a thin marginal lip extending around the toe and forepart of the sole and terminating adjacent the waist portion thereof, the waist and heel portions of the sole being left intact, subsequently lasting said sole and the shoe upper, with a reinforcing shank inserted within the waist and heel portion of the upper and against the last, inturning the lower edge portion of the upper within the recess formed between said marginal lip and the lower marginal portion of the sole, temporarily securing said inturned portion of the upper within said recess around the forepart of the sole and similarly securing the waist and heel part of the upper to said

shank between the shank and the sole, removing the upper with the temporarily attached sole from the last, permanently securing said inturned portion of the upper within said recess by stitches passing through said lip and lower marginal portion of the sole and said inturned portion

of the upper, and permanently securing the waist and heel part of the upper between said shank and the upper face of the sole by ¹⁰ nails or the like passing through the sole, the upper, and the shank.

In testimony whereof I affix my signature.
E. R. HAYDEN.
